(57) **CLAIM**

The ornamental design for a drying rack member as shown and described.

DESCRIPTION

FIG. 1 is a front perspective view of a clothes drying rack including a drying rack member.

FIG. 2 is a front perspective view of the drying rack member.

FIG. 3 is a left side elevation view of the drying rack member, the right side being a mirror image thereof.

FIG. 4 is a top view of the drying rack member, the bottom view being a mirror image thereof; and,

FIG. 5 is an end elevation view of the drying rack member, the opposite end being a mirror image thereof.

The broken lines shown in FIGS. 1 thorough 3 depict environmental subject matter that forms no part of the claimed design.
